UNITED STATES PATENT OFFICE.

ALEXANDER SAMUEL VOLPIAN, OF SAVANNAH, GEORGIA.

LAMP FILAMENT AND SUPPORT.

Application filed October 25, 1921. Serial No. 510,374.

To all whom it may concern:

Be it known that I, ALEXANDER S. VOLPIAN, a citizen of the United States, and a resident of Savannah, in the county of Chat-
5 ham and State of Georgia, have invented a new and Improved Lamp Filament and Support, of which the following is a description.

My invention relates to a filament and 10 support therefor for incandescent electric lamps.

The invention has for its general object to provide a filament and separated supporting elements therefor with which the filament 15 has contact at various points so that should the filament break or current be otherwise interrupted at one point in the total length of the filament, the remainder of the filament will be continued in circuit with the 20 supporting elements and illumination be maintained.

A more specific object of the invention is to provide a support for the filament of a character to prevent short-circuiting, as well 25 as to provide strength.

The nature of the invention and its distinguishing features and characteristics will more clearly appear as the description proceeds.

30 Reference is to be had to the accompanying drawing forming a part of this specification, in which the figure is a perspective view of a filament and support constituting an embodiment of my invention, it being understood that the drawing is merely illustrative of one example of the invention.

In carrying out my invention in accordance with the illustrated example, I provide a stem 10 forked at its outer end as at 10°, 40 the fork carrying a frame 11 preferably of ring form. A second stem 12 is provided, extending lengthwise of the stem 10 and forked at its outer end as at 12°, the fork carrying a frame 13 advantageously of ring 45 form and smaller than the frame 11.

A film 14 runs back and forth between the frames 11 and 13 laced about the latter or otherwise making an effective electrical contact therewith.

50 It will be clear that should the filament be broken or interrupted at a given point or points, the circuit will be completed through the remainder of the filament.

The stems 10 and 12 are separated 55 throughout their lengths to prevent short-circuiting. It will be readily understood

that the terminals of the stems 10 and 12 are insulated in the lamp plug in the usual manner.

I would state in conclusion that while the 60 illustrated example constitutes a practical embodiment of my invention, I do not limit myself strictly to the exact details herein illustrated, since, manifestly the same can be considerably varied without departure 65 from the spirit of the invention as defined in the appended claims.

Having thus described my invention, I claim:

1. A filament support having two ring- 70 like frames one within the other, and both disposed in a plane transverse to the longitudinal axis of the lamp enclosing said frame, and a filament running back and forth between said frames and alternately 75 making contact with the respective frames.

2. A filament support including separate 80 stems having forked outer ends, separated rings carried by the forks, and a filament running back and forth across the space between the frames, and contacting with the rings at separate points.

3. An incandescent lamp having separated 85 filament supporting elements presenting separated frames, in the form of concentric rings, and filament members extending across the space between said frames at intervals and in contact therewith to form electrical connections between the frames at different 90 points about the same, in a plane parallel with the plane of the radii of the rings.

4. A filament support comprising a frame 95 presenting a plurality of concentric rings each connected to an electrical terminal, and a filament running back and forth between said rings and in contact alternately and at spaced points therewith.

5. A filament support comprising a pair 100 of bifurcated frames each connected to the electrical terminals of a lamp, and each carrying adjacent their free ends a ring, and a filament running from one ring to the other at spaced points therewith.

6. In a filament support of the class described, a frame presenting a pair of rings 105 one concentric with the other and substantially in the same plane, each ring being connected to one electrical terminal of a lamp, and a filament running back and forth between said rings and connected thereto.
